BRAKE

Erwin F. Loweke, Detroit, Mich., assignor to Hydraulic Brake Company, Detroit, Mich., a corporation of California.

Application October 5, 1938, Serial No. 233,468

8 Claims. (Cl. 188—152)

This invention relates to brakes, and more particularly to brakes for motor vehicles.

An object of the invention is to provide a fluid pressure actuated motor including opposed pistons, and means intermediate the pistons for trapping fluid so as to retain one of the pistons against movement toward its retracted position.

Another object of the invention is to provide a fluid pressure actuated motor for actuating the friction elements of a brake structure, and to so construct the same that at least one of the elements may be held against movement toward its retracted position during actuation of the brake.

Other objects and advantages of the invention will appear from the following description taken in connection with the drawing forming a part of this specification, and in which—

Fig. 1 is a vertical sectional view of a brake embodying the invention;

Fig. 2 is a longitudinal sectional view of the fluid pressure actuated motor; and

Fig. 3 is a cross-sectional view of the motor, substantially on line 3—3, Fig. 1.

Referring to the drawing for more specific details of the invention, 10 represents a fixed support or backing plate adapted to be secured to an axle or to an axle housing, and associated with the backing plate is a rotatable drum 12 adapted to be secured to a wheel.

30 A pair of corresponding interchangeable friction elements or shoes 14 and 16 are pivotally mounted on the backing plate. Each of the shoes includes a web 18 supporting a rim 20 having secured thereto a lining 22 suitable for cooperation with the drum.

Adjustable retractile stops 24 suitably arranged on the backing plate support the shoes in proper spaced relation to the drum when in retracted position, and a retractile spring 26 connecting the shoes serves to return the shoes to the retracted position and to retain them against the stops when in such position.

45 A fluid pressure actuated motor 28 mounted on the backing plate and connected to the shoes as by thrust pins 30 and 32 serves to actuate the shoes into engagement with the drum against the resistance of the retractile spring 26. The motor includes a cylinder 34 having a large chamber 36 and a relatively small chamber 38 arranged in axial alignment with one another and separated by a diaphragm 40 having an annular rib 42, the purpose of which will hereinafter appear, and a concentric opening 44 providing a communication between the chambers. The chamber 36 is 50 provided with a port 46 connected as by a fluid

pressure delivery pipe or conduit 48 to a suitable source of fluid pressure. The chamber 36 also has a port 50 normally closed as by a bleeder screw 52, and, correspondingly, the small chamber 38 has a port 54 normally closed by a conventional bleeder screw, not shown.

A valve 56 in the chamber 36 is seated on the diaphragm 40 for control of the port 44. As shown, the valve includes a flexible cup including a disk 58 normally supported on the diaphragm with the annular rib 42 embedded therein so as to more effectively seal the disk to the diaphragm. The disk has a marginal lip 60 normally engaging the wall of the chamber 36 and a concentrically disposed opening 62, and a spring-rest 64 seated in the cup has a plurality of openings 66 therethrough arranged in a circle the center of which is in the axis of the opening 62.

A piston 68 reciprocable in the chamber 36 has a recess in its back for the reception of the thrust pin 30, and seated on the head of the piston is a sealing cup 70 held against displacement by a spring 72 interposed between the cup and the spring-rest 64. This spring also serves to retain the valve 56 on the diaphragm 40. Correspondingly, a piston 74 reciprocable in the small chamber 38 has a recess in its back for the reception of the thrust pin 32, and seated on the head of this piston is a sealing cup 76 held against displacement by a spring 78 interposed between the cup and the diaphragm 40.

In a normal operation, when fluid under pressure enters the chamber 36, the valve 56 opens and a part of the fluid passes through the valve into the chamber 38. This causes concomitant actuation of the pistons 68 and 74, and this actuation of the pistons results in moving the shoes 14 and 16 from their position of rest on the stops 24 into engagement with the drum 12 against the resistance of the retractile spring 26, so as to effectively apply the brake.

During a heavy or prolonged braking operation, the drum becomes distorted to a greater or less degree, due to the greater effectiveness of the forward braking shoe because of its self-energizing characteristic. This distortion of the drum impairs the effectiveness of the brake, and this condition may be avoided by controlling the friction elements or shoes so as to offer substantial resistance to any distortion of the drum that may occur during a braking operation. The desired control of the shoes may be effectively accomplished by interposing a simple valve 56 between the pistons 68 and 74 to trap the fluid in the small chamber 38 so as to retain the piston 74 against movement

and thereby inhibit movement of the reverse braking shoe toward its retracted position.

The valve 56 is of such structure that retrograde movement of fluid from the small chamber 38 is checked during a braking operation. Any tendency of such movement induced by distortion of the drum imparting movement of the reverse braking shoe 16 toward its retracted position causes the valve to close, and because of the differential of pressures in the chambers 36 and 38, and particularly because of the different areas of the valve subjected to these pressures, the valve is retained closed during a braking operation.

15 Upon conclusion of a braking operation, the pressure on the fluid is released, whereupon the valve 56 opens and the shoes 14 and 16 are returned to their retracted position under the influence of the retractile spring 26 connecting the 20 shoes; and as the shoes return to their retracted positions, the pistons 68 and 74 are moved to their retracted positions on the stops 24 against the resistance of the springs 72 and 78.

While this invention has been described in 25 connection with certain specific embodiments, the principle involved is susceptible of numerous other applications that will readily occur to persons skilled in the art. The invention is, therefore, to be limited only as indicated by the scope 30 of the appended claims.

Having thus described the various features of the invention, what I claim as new and desire to secure by Letters Patent is—

1. In a fluid pressure actuated brake, a motor 35 comprising a large chamber and a relatively small chamber, a diaphragm between the chambers having an opening, a piston reciprocable in each of the chambers, and a two-way valve seated on the diaphragm within the large chamber for control of the opening.

2. In a fluid pressure actuated brake, a motor comprising a cylinder having a large chamber and a relatively small chamber arranged concentrically of the large chamber, a diaphragm 45 separating the chambers having an opening providing a communication between the chambers, a piston reciprocable in each of the chambers, and a two-way valve seated on the diaphragm within the large chamber for control of the opening.

3. In a fluid pressure actuated brake, a motor comprising a cylinder having a large chamber and a relatively small chamber arranged concentrically of the large chamber, a diaphragm 55 separating the chambers having a concentric opening providing a communication between the

chambers, an annular rib on the diaphragm extended into the large chamber, a two-way valve seated on the diaphragm for control of the opening including a flexible cup adapted to imbed the annular rib on the diaphragm, said cup having an opening therethrough, and a disk in the bottom of the cup having openings therethrough offset with relation to the opening in the cup. 5

4. In a fluid pressure actuated motor, a cylinder, opposed pistons movable therein, and a 10 two-way valve between the pistons including a flexible sealing cup having a concentric opening, and a member in the bottom of the cup having openings therethrough offset with respect to the opening in the cup. 15

5. In a fluid pressure actuated motor for actuating the friction elements of a brake, a cylinder having a large chamber and a small chamber, a piston reciprocable in each of the chambers, a two-way valve separating the chambers 20 including a flexible cup seated on a shoulder at the junction of the chambers including a flexible cup having a concentric opening, a spring-rest seated in the bottom of the cup having openings therethrough offset with relation to the opening 25 in the cup, and a spring interposed between the spring-rest and one of the pistons.

6. A brake comprising a fixed support, a rotatable drum associated therewith, friction elements 30 on the support for cooperation with the drum, a motor on the support including a cylinder, a diaphragm in the cylinder having an opening therethrough, said diaphragm dividing the cylinder into two chambers, pistons in the chambers connected respectively to the friction elements, and a fluid pressure actuated valve on the diaphragm 35 for control of the opening.

7. A brake comprising a fixed support, a rotatable drum associated therewith, friction elements on the support for cooperation with the drum, a 40 motor on the support for actuating the friction elements including a double-diametral cylinder, opposed pistons movable in the cylinder, and a two-way valve in between the pistons including a flexible cup having a concentric opening and 45 a spring-rest seated in the bottom of the cup having openings therethrough arranged in a circle surrounding the opening in the cup.

8. In a fluid pressure actuated motor, a cylinder, opposed pistons movable therein, a valve 50 between the pistons including a sealing member having an opening therethrough, and a rigid member in the bottom of the sealing member having openings therethrough offset with respect to the opening in the sealing member. 55
